The ornamental design for an adhesive suitcase skin, as shown and described.

DESCRIPTION

FIG. 1 is a perspective view of an adhesive suitcase skin showing my new design;

FIG. 2 is a front elevation view thereof;

FIG. 3 is a rear side elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines depict unclaimed boundaries to the adhesive suitcase skin which form no part of the claimed design. The adhesive suitcase skin is shown with symbolic breaks in length. The appearance of any portion of the article between the break lines forms no part of the claimed design.
